SIFTPROOF BAG

James L. Shively, Camas, Wash., assignor to
 Crown Zellerbach Corporation, San Francisco,
 Calif., a corporation of Nevada

Application November 25, 1942, Serial No. 466,932

3 Claims. (Cl. 93—35)

This invention relates to the making of paper bags of the satchel bottom and similar types, and, more particularly, to the making of bags of such types which are required to be sift-proof, as, for example, bags in which carbon black is packed.

The object of my invention is to assure an absolutely leak-proof or sift-proof seam in the tube from which the bag is made.

Heretofore there have been frequent complaints, on the part of persons handling carbon black, that the paper bags in which such material is packed, often developed a small leak in the seam, causing puffs of black carbon to be expelled from the bag every time the bag is handled or touched, and causing the carbon contents gradually to leak out. Because of the peculiar nature of the carbon black in particular, a very small failure of the bag seam is sufficient to produce a serious leak when the bag is filled with such material.

By closely observing the paper bags in which carbon black is packed where such leaks occur, and after considerable experimenting in the making of such bags for the purpose of determining the cause of the development of such leaks, I finally discovered that the difficulty is attributable to certain faults in the making of the bag which I shall describe briefly.

These bags are generally and preferably made on machines in which the paper bag material is first formed into bag tubing with the seam of the tube at the top of the machine. Having the seam so located in the machine is an advantage in that it enables the operator to watch the initial tube-forming operation and the paste line more easily. The bottom of the bag is next formed at the end of each section of bag tubing and folded down on the seam side of the tube. Paste is used in the forming of the bag tubing in order to secure the overlapped edges together at the seam. The paste employed for this purpose requires some time in which to set, and until the paste has set the overlapping edges of the material at the seam may be moved slightly longitudinally, with respect to each other. It has not been found feasible, in bag-making machines, to use a strong quick-drying glue instead of such paste for forming the tube seam.

I have discovered that, in the forming of the bag bottom, the edges of the paper along the tube seam become displaced longitudinally to some extent at certain points where transverse folds occur, or may be separated from each other at or near such points, due to the fact that the paste, which has not had time to dry, does not hold the overlapped edges together firmly enough to enable the seam to be folded in the same manner as a single sheet or unitary structure. In consequence, either a slippage of one ply on the

other, or a separation of the plies, may occur whenever a transverse fold is made in the bag tube in the forming and folding down of the bag bottom. This slippage may result subsequently in the outer and inner laps at the seam parting very slightly, or it may result in one lap being pulled so much tighter than the other that when the fold is later straightened out, upon the filling of the bag, a rupture of the edge of one of the plies will occur at this point. In either case a leak develops in the filled bag as a result. In a multi-ply bag the same situation exists more or less in the seams of all the plies wherever failures occur, but of course the most important seam to be kept leakproof in a multi-ply bag is the seam of the outer plies.

I thus discovered that practically all the imperfections in the bag seams, which produced leaks in the bags or which caused a rupture in the bag seams which in turn produced the leaks, were due to such displacement, disarrangement or separation of the lapped, pasted edges at some point along the seam where a fold had occurred during the completion of the bag bottom. The object of my present invention consequently has been to avoid the occurrence of such imperfections in the seam.

I have found that these difficulties may be successfully overcome and prevented by cementing a binder strip over the bag tube seam immediately with the forming of the bag tube. The face of the binder strip which I use for attaching to the tube at the seam is previously coated with a strong adhesive of the type commonly used on binder tape or gummed tape. This adhesive consists of strong glue of some form or other which, upon being moistened, is rendered temporarily in a tacky condition but which then immediately dries again. When the binder strip is applied to the tube seam, after the seam has been pasted, the adhesive on the binder strip, although it has been rendered tacky, by moistening or by other treatment, dries almost immediately and much more rapidly than the paste in the seam, with the result that the overlapped edges of the bag tube are firmly held at the seam even though the paste in the seam has not yet become dry. In carrying out my method I form the bag tube and the pasted seam in the usual manner and apply strong gummed tape, of a width sufficient to extend some distance on each side of the seam, on top of the seam, the adhesive on the tape having first been rendered tacky. The tape or binder strip is immediately pressed down firmly on the seam, and, if necessary, heat may even be applied, although this will generally not be necessary. The bag tube is now ready for the bottom-folding operation, and since the binder strip holds the plies of the seam firmly the overlapped edges of the seam, even though the paste in the seam has not

yet dried, will not slip on each other during the folding of the tube, but the plies at the seam, together with the binder strip, will form a unitary structure and this structure will be preserved during the folding. Thus the primary purpose of the applied binder strip is to hold the seam tight during the folding and until such time as the paste in the seam is thoroughly dry. The effect of this application with the binder strip along the bag seam can be explained more fully with reference to the accompanying drawings in which:

Fig. 1 is a perspective view of a section of paper bag tubing ready for the bottom-forming operation, the seam in the bag tubing having been formed in accordance with my invention;

Fig. 2 is a fragmentary view, in perspective, of an end of the bag tubing showing more clearly the improved manner of forming the seam;

Fig. 3 illustrates the paper bag tubing of Fig. 1 during one stage in the forming of the bag bottom;

Fig. 4 shows the completed bag with the bottom entirely formed;

Fig. 4A shows the bottom portion of an ordinary completed bag in which the seam has been formed merely in the conventional manner;

Figs. 5 and 5A are diagrammatic views illustrating the effects produced by the transverse folds at the bag seam of an ordinary bag in the forming of the bottom;

Fig. 6 is a fragmentary side elevation of an ordinary bag in use showing the resulting leakage points; and

Fig. 7 is a diagrammatic elevation of an apparatus adapted to carry out my invention on a conventional bag-forming machine.

Referring first to Figs. 1 and 2, the bag tubing 13 is formed on a bag-making machine in the conventional manner which includes the lapping of one longitudinal edge 11 of the sheet over the other longitudinal edge 12 and the securing of the two overlapped edges together by a film of paste between them. As previously explained, this paste requires considerable time in which to dry, and it has not been found feasible in bag machines to substitute other adhesive means in place of the usual paste.

Immediately upon forming of the seam in the conventional manner I apply a strip of gummed tape 10, constituting a seam binder strip, over the entire seam. This binder strip, or gummed tape, is preferably made of heavy paper, or similar suitable material, one face of which carries a coating of glue which has been dried. Prior to the application of the binder strip to the seam the glue is moistened. This renders the glue tacky so that the binder strip will then adhere very strongly to any surface with which its glue-treated face comes into contact. However, after such moistening, the glue again dries very quickly, and consequently the binder strip must immediately be applied to the seam. The width of the binder strip 10 must be sufficient to enable the strip to extend a distance on each side of the seam (as shown in Fig. 2) to enable the binder strip to have a firm hold on both plies adjoining the seam. The result is that the two plies will be held so strongly in place that the subsequent manipulation and folding of the tube, which takes place in the forming of the bag bottom, will not cause the overlapped edges 11 and 12 of the seam to slide one upon the other, or separate, even though the film of paste between them has not yet dried.

In Fig. 3 the bag bottom is shown in the process of formation at one end of the section of the bag tube. This figure illustrates the forming of what is commonly known as a "satchel" type of bag bottom. A transverse fold has been made across the seam of the tubing on the line 14. Subsequent transverse folding also takes place on the lines 15 and 16 in the forming of the bottom, the fold on the line 15 also being made across the seam. When paste has been applied to the bottom flaps 17 and 18 and these flaps are folded, one over the other, the forming of the bag has been completed. Fig. 4 shows the bag finished and now ready for use. In order to explain more clearly how the particular problem, with which my invention is concerned, arises, I shall describe briefly what occurs when a similar bag bottom is formed on bag tubing when my invention is not used. Fig. 4A shows the corresponding bottom of an ordinary bag having the usual seam 19 in the bag tubing, and showing the bottom as formed in exactly the same manner as in the bag of Fig. 4. The transverse folds 14a, 15a and 16a correspond to the folds 14, 15 and 16 respectively in Figs. 3 and 4. In Figs. 5 and 5A the two overlapping edges of the bag tubing material at the seam of the bag (constituting the seam 19 in Fig. 4A) are designated by the reference characters 20 and 21, and the film of paste between the overlapping edges at the seam is indicated by the heavy line 22. When the transverse fold 14a is made across the bag seam, assuming that the paste film 22 has not yet entirely "set" or dried, there will be a tendency for the lap 21 to slide slightly with respect to the lap 20 in either or both of the directions indicated by the arrows x and x' and approximately at the places where these arrows are shown. Similarly when the next fold 15a is made, the tendency will be for the lap 20 to slide with respect to the lap 21 as indicated by the arrows y and y'. If the two overlapping edges were entirely free to slide at all points with respect to each other, the opposite tendencies and motions indicated at x and y' might compensate each other. However, upon the subsequent straightening out of the folds the tendencies would be reversed. To a modified degree this is what might occur if the paste film in between offered no resistance. The paste film however does offer some resistance and the amount of resistance will depend largely upon the extent to which the paste has become "set." If the paste were entirely "set" before any folding took place the paste film would presumably be strong enough to hold the overlapping edges firmly together and prevent any longitudinal movement of one with respect to the other. Under such conditions the lapped edges and "set" paste film would constitute a unitary structure and would behave like a single thick ply of paper under the folding. Actually the paste film at best will be only slight or partly "set" when the folding occurs. The tendency of the lapped edges to move with respect to each other may be sufficient to break the partly "set" paste film in which case a weakened paste line will result. On the other hand, if the paste film is partly "set" the previously-described tendencies may only force the adjacent laps slightly apart at certain points, such as those indicated at z in Fig. 5A.

The effect of these weaknesses, either total or partial failures, in the paste seam, will be appreciated with reference to Fig. 6 in which an ordinary bag 23 having such defects in the seam is assumed to have been filled with a substance such

as carbon black. In the bag 23 the broken line 24 indicates the original fold line 14a of Figs. 5 and 5A, while the bottom edge line 25 corresponds to the fold line 15a of Figs. 5 and 5A. Not only will leaks occur on or near these fold lines but I have also discovered that when a heavy strain is placed on the bag, since one of the lapped edges is pulled tighter than the other at the fold line, the more tightly stretched edge of the material will tear apart, as illustrated at 26, whereupon the failure of the bag becomes even more serious. The rupture 26 has been somewhat exaggerated in Fig. 6 for the purpose of illustration.

With the use of my invention, as previously explained, the tendency of the overlapped edges of the seam to slip with respect to each other, or to separate at points on or adjacent the fold lines, is successfully resisted, since the gummed tape, or binder strip, holds the two edges of the material firmly together at the seam until the paste film is entirely "set." Although the binder strip then remains attached to the bag tubing, and to some extent continues to be a reinforcing for the bag, its real purpose is accomplished as soon as the paste seam has entirely "set," for presumably the film of paste itself would then provide a sufficient hold to prevent any leak occurring along the seam.

In Fig. 7 I have indicated a simple and practical apparatus which has been successfully employed, in combination with a well-known type of bag-forming machine, for carrying out my invention. In this figure the bag tubing 27, which it is assumed has been formed in the usual manner with the pasted seam at the top of the machine, is moving in the direction indicated by the arrow. A roll of gummed tape 28 is mounted on the machine above the bag tubing and in line with the seam of the bag. The gummed tape passes through a dispenser 30, which dispenser includes means for moistening the glue on the lower face of the gummed tape. After leaving the dispenser 30, the gummed tape passes under a guide pulley 31 and finally becomes attached along the seam of the bag tubing, as the tubing and binder strip are together drawn between a pair of draw rolls 32. After the binder strip has thus been firmly attached to the bag tubing along the seam, the bag tubing is cut into the desired lengths for the bags in the usual manner, by a chain or knife cutoff 33. From this point on the formation of the bag continues in the usual manner.

I claim:

1. In the making of a bag of the character described having a longitudinal seam and a bag bottom folded over on the seam, the improved method of forming the longitudinal seam and of preventing failure in the same without delaying the completion of the bag, said method comprising arranging the bag material so that the longitudinal edges overlap at the seam and applying a film of ordinary, slow-drying paste between the overlapped edges, arranging a binder strip for application longitudinally along the seam, having said binder strip of sufficient width to provide for overlying the outside surface of the bag a substantial distance on both sides of said seam and having the underside of said binder strip covered with a tacky, quick-drying adhesive, positioning said binder strip on the surface of said bag material so that said strip will overlie the surface on both sides of said seam, pressing

said binder strip firmly against said surface, and forming the bag bottom without waiting for said slower-drying film of paste between said overlapped edges of said bag material to "set," whereby said binder strip will cause said overlapping edges to act as a unitary structure during the folding of the bag bottom and prevent any movement of one edge with respect to the other pending the permanent "setting" of said slower-drying film of paste.

2. In the making of a bag of the character described having a longitudinal seam and a bag bottom requiring transverse folds across the seam, the improved method of forming the longitudinal seam and of preventing failure in the same without delaying the completion of the bag, said method comprising forming the bag material into a bag tubing by overlapping the longitudinal edges and securing the same together by a film of slow-drying paste, arranging a binder strip for application longitudinally along the seam, having said binder strip of sufficient width to provide for overlying the outside surface of the bag tubing a substantial distance on both sides of said seam and having the underside of said binder strip covered with a quick-drying adhesive capable of forming an immediate strong bond between said strip and the surface of said bag tubing, positioning said binder strip on the surface of said bag tubing so that said strip will overlie the surface on both sides of said seam, pressing said binder strip firmly against said surface, whereby said binder strip will cause said overlapping edges to act as a unitary structure during the folding of the bag bottom and prevent any movement of one edge with respect to the other pending the permanent "setting" of said slower-drying film of paste.

3. In the making of a bag of the character described having a longitudinal seam and a bag bottom requiring transverse folds across the seam, the improved method of forming the longitudinal seam and of preventing failure in the same without delaying the completion of the bag, said method comprising arranging the bag material so that the longitudinal edges overlap at the seam and applying a film of ordinary slow-drying paste between the overlapped edges, arranging a binder strip for application longitudinally along the seam, having said binder strip of sufficient width to provide for overlying the outside surface of the bag a substantial distance on both sides of said seam and having the underside of said binder strip treated with a coating of glue and said glue allowed to dry, said glue having the property of drying quickly when moistened, moistening said glue immediately before applying said strip to the bag material sufficiently to cause said glue to become momentarily tacky and then quickly set again, positioning said binder strip on the surface of said bag material so that said strip will overlie the surface on both sides of said seam, pressing said binder strip firmly against said surface, and forming the bag bottom without waiting for said slower-drying film of paste between said overlapped edges of said bag material to "set," whereby said binder strip will cause said overlapping edges to act as a unitary structure during the folding of the bag bottom and prevent any movement of one edge with respect to the other pending the permanent "setting" of said slower-drying film of paste.

JAMES L. SHIVELY.
